CLAIM

The ornamental design for a torchiere lamp, as shown and described.

DESCRIPTION

FIG. 1 is a full front elevational view of a first embodiment of my new design;

FIG. 2 is a full front elevational view of a second embodiment thereof;

FIG. 3 is an enlarged detailed perspective view of Embodiment 1;

FIG. 4 is an enlarged detailed perspective view of Embodiment 2;

FIG. 5 is an enlarged detailed front elevational view of Embodiment 1;

FIG. 6 is an enlarged detailed front elevational view of Embodiment 2;

FIG. 7 is an enlarged detailed right side elevational view of Embodiment 1;

FIG. 8 is an enlarged detailed right side elevational view of Embodiment 2;

FIG. 9 is an enlarged top plan view of Embodiment 1;

FIG. 10 is an enlarged top plan view of Embodiment 2;

FIG. 11 is an enlarged bottom plan view of Embodiment 1; and,

FIG. 12 is an enlarged bottom plan view of Embodiment 2. The broken lines shown in the drawing are environmental only and form no part of the claimed design.
